CLAIM

We claim the ornamental design for a football-shaped cutting board with wine and cheese tools, as shown and described.

DESCRIPTION

FIG. 1 is a perspective view of a football-shaped cutting board with wine and cheese tools, showing our new design with a drawer for the tools in an extended position;

FIG. 2 is a top plan view of FIG. 1;

FIG. 3 is a perspective view thereof, illustrated with the drawer in a retracted position;

FIG. 4 is a front elevational view of FIG. 3;

FIG. 5 is a rear elevational view of FIG. 3;

FIG. 6 is a left-side elevational view of FIG. 3, the right-side elevational view being a mirror image thereof;

FIG. 7 is a top plan view of FIG. 3; and,

FIG. 8 is a bottom plan view of FIG. 3.

The broken lines showing wine and cheese tools in FIGS. 1 and 2 and foot pads and a drawer recess in FIG. 8 depict environmental matter and form no part of the claimed design.
